WRAPPING MACHINE

Donald M. Houpt, Palestine, Ill.

Application June 2, 1936, Serial No. 83,121

8 Claims. (Cl. 93—2)

This invention relates to wrapping machines and has particular reference to that type commonly referred to as semi-automatic because of the fact that a portion of the wrapping operation is manually performed and the remainder is mechanically performed.

An object of the invention is to facilitate the ease and speed with which articles of varying size may be wrapped efficiently in such manner that they are ready for sealing as soon as removed from the machine.

An important feature of the invention resides in a combination and arrangement of parts whereby operation of the machine is the essence of simplicity and the cost of production thereof is reduced to a minimum. A further important feature of the invention resides in the association of the various elements with one another in such way that the machine may readily be adjusted to handle articles of widely divergent size.

While the machine illustrated and described herein is peculiarly suitable to the wrapping of bread loaves, it will be apparent that the mechanism is operable equally satisfactorily with other articles.

Various other objects and meritorious features of the invention will become apparent from the following description taken in conjunction with the drawings wherein like numerals refer to like parts throughout the several figures, and wherein:

Figure 1 is a top plan view of the machine;
Figure 2 is a side elevation;

Figure 3 is an end view through the article-receiving trough;

Figure 4 is a view similar to Figure 3 showing a different stage of the wrapping operation;

Figure 5 is an end elevation of the machine,

40 and

Figure 6 is a section through the center of the trough.

Referring now to the drawings, the mechanism is supported upon two longitudinally extending frame members 10 and 12 between which at spaced points extend stretchers 14 and 16. The stretchers are provided with rack teeth as indicated at 18 and 20, which teeth are adapted to cooperate with pinions 22 and 24 fixedly secured to a longitudinally extending shaft 26 provided with a knurled hand wheel 28 at its outer extremity. The shaft 26 is rotatably journaled in side frame 30, the other side frame 32 being fixed with relation to its supporting base. It will therefore be seen that rotation of the knurled hand

wheel 28 causes the side frame 30 together with the elements supported thereby to move toward or away from side frame 32.

Secured to side frame 32 is a wrapper support 34 and a wrapper guide 36 is adjustably positioned at the rear thereof by means of a slidable bracket 38 which may be secured in any adjusted position with reference to supporting frame 32 by means of the wing nut 40. One or both sides of the wrapper support may be provided with a side wrapper guide 42 to aid in positioning a stack of wrappers in proper relation to the rest of the mechanism.

When the side frame member 30 is drawn toward its opposite frame member 32 it slides underneath the wrapper support. Each of the side frame members 30 and 32 is shaped to provide a trough or channel, broadly indicated in Figure 2 by the numeral 44, extending transversely across the machine. Pairs of oppositely disposed channel guides 46 and 48 are secured to each of the side frame members and are so arranged as to telescope one over another when the space between the side frame members is reduced by rotating the hand wheel 28. This feature is clearly illustrated in Figure 1 of the drawings. Wrapper guides 50 are associated with channel guides 46 by pin and slot connections as indicated at 52 so that the said guides are adjustable.

Telescoping channel bottom members 54 and 56 are secured to the side frame members in such manner that they telescope in the manner heretofore described with relation to the channel guides 46 and 48.

End folding mechanisms of identical structure are associated with the ends of the channel or trough, being supported respectively by frame members 30 and 32, and comprise end folders consisting of wings 58 and 60 inclined in a direction substantially normal to each other and pivoted substantially at their intersection upon a pin 62 journaled in ears 64 which extend upwardly from the bottoms of the channel. A pin 66 journaled in a bracket 68 secured to each side frame member at the base of the channel functions as a pivotal support for an auxiliary end folder 70.

Auxiliary end folder 70 is normally urged toward its most inward position, as shown in Figure 5, by a spring 72. A one-way connection provided by lateral arms 74 and 76 extending from pins 62 and 66 respectively transmits the spring tension to the winged end folders and normally retains them in the position indicated in Figure 5, the bottom wing 58 being raised somewhat 55

from and extending at an angle to the channel bottom. It will be apparent from Figure 2 of the drawings that wing 60 of each end folder is bifurcated to permit passage therethrough of the auxiliary end folder 70 for a purpose to be described more fully hereinafter.

Each of the channel guides 46 and 48 is adjustable longitudinally of the frame structure through pin and slot connections indicated at 78, 10 thereby permitting adjustment of the width of the channel. Both pairs of channel guides 46 and 48 are movable in order to center the article to be wrapped in relation with other parts. Each pair, in addition, is provided with pin and slot 15 connections as indicated at 80 to secure the telescoping guides in any relative position to which they are moved by means of the hand wheel 28. Each channel of each pair of channel guides 46 and 48 is provided with a slot 82 for a purpose to 20 be brought out hereinafter.

Pivoted to side frames 30 and 32 respectively at 84 and 86 by means of arms 88 and 90 are so-called side end folders 92 and 94. Actuating link 96 is pivotally secured to arm 88 as indicated at 25 98 and is connected by a lost-motion connection provided by slot 100 with a pin 102 extending laterally from arm 90 below its pivot point.

Links 104 are pivotally connected as at 106 to frame ears 108 and are pivotally connected at 30 110 to the ends of actuating links 96. An operating bar 112 is fixedly secured to the upper end of one link 104 and is slidably supported at its other end in the bracket 114 which is secured in some suitable fashion to the end of the opposite 35 link 104, as indicated at 116. Some suitable mechanism, such as coil springs 118, functions to yieldably retain the side end folders 92 and 94 in withdrawn position as illustrated in Figure 2.

Inasmuch as the mechanism illustrated herein 40 has been described as particularly adapted for use in wrapping bread loaves, the operation of the device will be described accordingly. A wrapper sheet is first withdrawn by the operator from the wrapper support 34 and positioned across 45 the channel 44, the guide 50 functioning to properly center the wrapper over the channel. The bread loaf is preferably inverted and positioned over the center of the wrapper sheet. The bread is then dropped or lowered into the channel 50 44, auxiliary end folders 70 and bifurcated end folders 60 being in the position illustrated in Figure 5 at the beginning of this operation. As the bread with its wrapper descends into the channel, the protruding ends of the wrapping 55 sheet, which is of course of substantially greater length than the bread loaf being wrapped, are contacted by auxiliary end folders 70 which function to form an initial upward tuck t along the center of the lowermost portion of the wrap- 60 per ends. Further lowering of the article will cause it to contact wings 58 of the end folders 60. These are forced into horizontal position with continued lowering of the article, thereby forcing the bifurcated end folders 60 up against 65 the projecting ends of the wrapper to thereby complete the tuck started initially by the auxiliary end folders and hold the bottom edge of the wrapping paper up against the ends of the bread. During this inward movement of the end folders 70 the auxiliary end folders 70 have been forced out- 75 wardly against the resistance of spring 72 by the one-way connection hitherto described to thereby get the same out of the operator's way. Channel guides 46 and 48 form the wrapper sheet around the sides of the loaf as it descends to the bottom

of the channel 44. The sides of said wrapper sheet are lapped over the loaf manually as indicated at 1 after the loaf with its wrapper has descended to the bottom of the channel. The bread and wrapper at this stage of the operation 5 is most clearly illustrated by Figure 3 taken in conjunction with Figure 6.

The operator then leans against bar 112, or exerts pressure against the same in some other way, thereby moving links 104 to operate actuating links 96, which in turn force the side end folders 92 and 94 at each end of the bread loaf inwardly to perform their intended function. It is to be noted that movement of the side end folders does not begin simultaneously, side end 15 folders 92 being started on their inward movement immediately upon movement of link 104 and side end folders 94 lagging somewhat behind in their initial movement by virtue of the lost-motion connection at 100-102. It will therefore be seen that movement of bar 112 first forces inwardly side end folders 92 to force one side end flap f of the wrapper inwardly against the end of the bread, the other side end folders 94 coming in subsequently on continued movement of the bar 112 to force the other side end flap f' inwardly against the end of the bread. This phase of the operation is most clearly indicated by Figure 4 of the drawings.

Each pair of side end folders 92 and 94 are off- 30 set in such way that the two overlap when the side end folding operation is completed. The operator then folds down the top end flaps m manually and grasps the ends of the bread through the openings provided by the bifurcations in end folder wings 60. Grasping the wrapped loaf in this way retains the other flaps properly folded. Release of pressure on bar 112 permits side end folders 92 and 94 to return to idle position as shown in Figure 2, leaving the 40 wrapped loaf in position for removal. The operator can then remove the package for sealing.

As hitherto stated the length of the channel may be varied by drawing in the side frame 30 through operation of hand wheel 28. The width 45 of the channel may be variably adjusted through the adjustability of guide channels 46 and 48. Wrappers of various sizes may be accurately positioned on the wrapper support 34 through the adjustability of guides 36 and 50. It will be 50 apparent that on withdrawal of the wrapped article from the channel 44, spring 72 will force the auxiliary end folders 70 inwardly from the position illustrated in Figure 6, forcing the bifurcated end folders back into the position illustrated in Figure 5 through the one-way connection afforded by arms 74 and 76.

As has been hitherto indicated, the gist of this invention resides in the semi-automatic features described and the arrangement whereby various operations are performed in timed relation to one another to obtain most effective and rapid wrapping action by the operator. Various modifications of the specific mechanical movements whereby these successive timed operations are obtained will be manifest to those skilled in the art and for that reason I wish to limit myself only within the scope of the appended claims.

What I claim is:

1. A semi-automatic wrapping machine including in combination framework providing a trough for receiving the article to be wrapped and a wrapper support adjacent the top thereof, auxiliary end folders oppositely disposed at the ends of the trough operable to form an initial inward 70 75

- tuck in the prolonged bottom sides of a wrapping sheet previously placed under the article, end folders similarly disposed including means automatically operable on descent of the article into the trough for drawing end folding portions inwardly to complete said inward tuck, and side end folders movable in a plane normal to that of the end folders for tucking in the side flaps formed by the end tucks. 5
- 10 2. A semi-automatic wrapping machine including in combination framework providing a trough for receiving the article to be wrapped and a wrapper support adjacent the top thereof, auxiliary end folders oppositely disposed at the ends of the trough operable to form an initial inward tuck in the prolonged bottom sides of a wrapping sheet previously placed under the article, end folders similarly disposed including means automatically operable on descent of the article into the trough for drawing end folding portions inwardly to complete said inward tuck, side end folders movable in a plane normal to that of the end folders for tucking in the side flaps formed by the end tucks, and a single manually operable 15 means for actuating said side end folders. 20
- 25 3. A wrapping machine including in combination framework providing a trough for receiving the article to be wrapped and a wrapper support adjacent the top thereof, auxiliary end folders oppositely disposed at the ends of the trough and operable to form an initial inward tuck in the prolonged bottom sides of a wrapping sheet previously placed under the article, end folders similarly disposed including means automatically operable on descent of the article into the trough for drawing end folding portions inwardly to complete said inward tuck, means connecting said auxiliary end folders and said end folders respectively whereby the former are moved outwardly as the end folders complete the inward tuck, and side end folders movable in a plane normal to that of the end folders for tucking in the side flaps formed by the end tucks, said connections between the auxiliary end folders and end folders including means for automatically returning the same to their initial position on removal of the wrapped article. 30
- 40 4. A wrapping machine including in combination framework providing a trough for receiving the article to be wrapped, bifurcated end folders operable inwardly automatically on descent of an article having a wrapper previously placed thereunder to form end tucks along the bottom of said article, and means operable by a single member for successively tucking the two side end flaps 45
- 45 thus formed at each end against the end of said article. 5
5. A wrapping machine including in combination a supporting frame, vertically disposed side frames positioned thereby in substantially parallel spaced relation, means for moving one side frame with reference to the other, and means associated with said side frame members providing a substantially rectangular trough adapted to receive an article to be wrapped, said means including 10 telescoping side channel and bottom members secured to the oppositely disposed side frames. 15
6. A wrapping machine including in combination a supporting frame, vertically disposed side frames positioned thereby in substantially parallel spaced relation, means for moving one side frame with reference to the other, means associated with said side frame members providing a substantially rectangular trough adapted to receive an article to be wrapped, said means including 20 telescoping side channel and bottom members secured to the oppositely disposed side frames, and means for adjustably positioning the channel side members to vary the width of said trough. 25
7. In combination with a wrapping machine 25 having a troughlike depository for the article to be wrapped, end folders comprising intersecting wings inclined substantially normally to each other and pivoted along substantially their intersection, a bifurcation in the upstanding wing of 30 said end folder, an auxiliary end folder of substantially greater height than said bifurcated wing pivoted about an axis substantially parallel to that of said end folder and adapted to swing through the bifurcation therein, yieldable means 35 normally retaining said auxiliary end folder at its innermost position, and a connection between said auxiliary end folder and said end folder whereby inward movement of said bifurcated wing positively forces said auxiliary end folder 40 outwardly. 45
8. A semi-automatic wrapping machine including in combination framework providing a trough for receiving the article to be wrapped, auxiliary end folders oppositely disposed at the ends of the trough operable to form an initial inward tuck in the prolonged bottom sides of a wrapping sheet previously placed under the article, end folders similarly disposed including means automatically operable on descent of the article into the trough for drawing end folding portions inwardly to complete said inward tuck, and side end folders movable in a plane normal to that of the end folders for tucking in the side flaps formed by the end tucks. 50

DONALD M. HOUPP.
